JAMES A. GRAY, OF SAN FRANCISCO, CALIFORNIA, ASSIGNOR TO AMERICAN CAN COMPANY, OF SAN FRANCISCO, CALIFORNIA, A CORPORATION OF NEW JERSEY.

APPARATUS FOR CUTTING AND APPLYING RING-LINERS.

1,162,155.

Specification of Letters Patent. Patented Nov. 30, 1915.

Application filed April 16, 1914. Serial No. 832,261.

To all whom it may concern:

Be it known that I, JAMES A. GRAY, a citizen of the United States, residing in the city and county of San Francisco and State of California, have invented certain new and useful Improvements in Apparatus for Cutting and Applying Ring-Liners, of which the following is a specification.

The present invention relates to an apparatus for the cutting from a disk blank an annular or ring liner for use in applying to the circumferential flange of can ends or covers, the object being by a single operation of the cutting mechanism to properly trim the disk blank, to sever therefrom the desired annulus or ring liner and at the same time remove the core section thereof, thereby accomplishing by a single acting punch means that which heretofore has required the action of two punches to successfully carry out.

Usually, in the cutting of ring liners for the flange of can ends or heads, a traveling web is employed from which the annulus to be removed or severed is first presented to the action of a punch for removing therefrom the central core, and thereafter the said web is acted on by a second punch or die of a diameter slightly larger than that of the first punch or die for the removal therefrom of the annulus or ring liner. It is the employment of this intermittent traveling web that the present machine successfully overcomes, permitting the utilization of disk blanks for the cutting of the ring liner therefrom and by so doing simplifying the construction of the apparatus, reducing the expense incident thereto to a minimum and at the same time materially increasing the output of ring liners.

To comprehend the invention, reference should be had to the accompanying sheets of drawings, wherein—

Figure 1 is a side view in elevation of the improved cutting apparatus, illustrating the same as applied to means for receiving the cut annulus or ring liners and can ends or covers and for applying the said liners to the flange of the can ends or covers, also disclosing the means for actuating the various working parts of the said cutting apparatus, the feed mechanism for the disk blank being disclosed. Fig. 2 is a longitudinal sectional view taken through the reciprocating die punch mechanism and the stationary as- sociated die, disclosing in part section one of the pockets of a rotary disk carrier for receiving the cut annulus or ring liners, the means for feeding the cut annulus therein, and the reciprocating plungers working within the said pocket for applying the said annulus to the flange of a can end or cover, said view also illustrating the manner of disposing of the central core removed from the disk blank during the operation of cutting the annulus or ring liner therefrom. Fig. 3 is a plan view disclosing the sizes and positions of the center core, annulus or ring liner and the trimmed waste relative to the disk blank from which the annulus or ring liner is to be severed. Fig. 4 is a plan view partly in section of the stationary die, the reciprocating die punch and the parts associated therewith, the same being illustrated in an unoperated position, said view illustrating the picker or extracting means for the removal of the waste material trimmed from the disk blank. Fig. 5 is a similar view of the said parts in operated or closed position, the means for extracting the waste material cut from the disk blank being removed. Fig. 6 is an enlarged broken detail view of the parts shown in Fig. 5 of the drawings, illustrating the picker or extracting means partly in its inward position. Fig. 7 is a vertical part sectional view taken on the irregular line $x-x$ Fig. 1 of the drawings, disclosing the picker or extracting means as having removed and released for discharge the trimmed waste material of the blank. Fig. 8 is a view similar to Fig. 7 of the drawings, illustrating the position of the picker or extracting means as about to engage the waste of the blank for removal. Fig. 9 is a perspective view of the trip means for actuating the nipper finger or jaw of the picker or extracting means. Fig. 10 is an enlarged detail part sectional view of the mechanism for removing the disk blanks successively from the stack within the holder and for delivering the same to the feed runway for the positioning thereof relative to the cutting mechanism. Fig. 11 is a plan view of the parts disclosed by Fig. 10 of the drawings. Fig. 12 is a vertical sectional view taken on line $y-y$ Fig. 10 of the drawings.

In the drawings, the numeral 1 is used to designate any suitable form of a supporting frame capable of sustaining the working

parts of the apparatus, which frame is provided with a bed plate 2. Within the frame 1 and secured on a longitudinal shaft 3 working in bearings 3' is situated a vertically disposed carrier disk 4, the said disk being provided with a series of transversely circumferentially disposed semi-circular seats or pockets 5. Within each of said seats or pockets work a pair of opposing normally spaced reciprocating plungers 6 and 6', the stems 7—7' of which extend through guides 8, and each of said stems carries at its outer end a depending roll 9. Each of the rolls works within a circumferential cam groove 10 of the fixed spaced disks 10', between which disks the carrier disk 4 revolves, and during the rotation of said carrier disk the plungers 6 and 6' are moved toward and from each other for applying the hereinafter described cut ring liner onto the flange of a can end or cover held therein, Figs. 1 and 2 of the drawings.

Each of the circumferential seats 5 of the carrier disk 4 is intersected by the spaced segmental peripheral openings 11 and 12, through which respectively the cut annulus or ring liners and the can ends or covers are delivered into the said seats 5 in spaced relation to each other between the opposing faces of the plungers 6 and 6', the can ends, heads or covers 13 being delivered into the seats of the disk carrier through the opening 12 in any suitable manner.

On the bed 2 and within a longitudinal guide-way 14 thereof works a reciprocating slide 14' carrying at its inner end two concentric die punches 15 and 15', there being interposed between said punches a longitudinally movable die ring 16, which die ring 40 registers with the opposing stationary die ring 17 held to the ring 17' of the cylindrical magazine 18, when the reciprocating slide 14' carrying the die punches is moved inward its full distance. The stationary die ring 17 is embraced by the follower ring 18' held to the fixed base ring 17' by the collar 19, the said follower ring being normally held outwardly pressed by the springs 19' interposed between the base ring 17' and the bottom face of the follower-ring, Figs. 2 and 4 of the drawings.

On a bracket 2' upwardly projecting from the bed 2 is mounted at one side of but adjacent to the punch mechanism, a holder 20 for the stack of horizontally disposed fibrous disks 21 from which the annulus or ring liners are to be cut—Figs. 1, 10, 11 and 12 of the drawings. The holder 20 is an open bottom one, the stack of disks 21 resting on the shelves or ledges 22 thereof, and the same are removed successively from within the holder by the hereinafter described sucker-arm outwardly projecting from a rock-shaft 20'. This shaft works within a suitable bearing and carries at one end a

pinion 21', which meshes with a bevel gear 23 secured to a rock-shaft 23'. This rock-shaft is provided at its outer end with a crank-arm 24 which is connected by a pitman 25 to a wrist-pin 26 projecting from the disk 26' secured to the inner end of a longitudinal shaft 27, to which shaft rotary motion is imparted from the drive shaft 28 by means of the bevel pinion 29 on the shaft 27 meshing with the bevel gear 30 on the shaft 28. Suitably connected to and thrown into action by the movement of the shaft 20' is a sucker arm 31, which is connected by an air connection 32' to suitable suction means. As the arm 31 is thrown upwardly against the under exposed face of the lowermost disk of the stack of disks held within the holder 20, the air suction causes the same to adhere firmly to the said sucker arm, so that when the arm 31 is lowered or swung downwardly, the lowermost disk of the stack of disks is removed from within the holder 20 and delivered into the vertically disposed feed chute 32. The air suction is destroyed as the arm 31 reaches its lowermost position, so as to release the removed disk, said air connection being broken by the port *a* in its hinged connection moving out of registry with the open port *b* (Fig. 11), thus destroying the air suction through the hollow sucker arm 31 and allowing air to enter between the disk and the edge of the sucker, and the removed disk blank to fall from the open end thereof. The disks 21 are thus successively removed from the holder and delivered into the feed chute 32 and by said chute discharged into the semi-circular seat 33 for positioning between the faces of the reciprocating die punch and the fixed die, being held thereto against lateral displacement by the weight of the light hinged holder 33'—Figs. 7 and 8 of the drawings. At the same time the deposited disk is prevented from falling from within its seat by means of the laterally movable slides 34 and 34', which are moved inwardly and outwardly during the reciprocating movement of the slide 14' by means of the horizontally swinging fulcrumed arms 35, suitably connected at their forward ends to said slides. The rear end portion of each arm is formed with an irregular slotted section, as shown at *c*, and connected by the pins 36 to a cross-head 36' carried by the reciprocating slide 14', the action of the fulcrumed arms 35 being such that the slides 34 and 34' are moved outwardly from within the sphere of the cutting punches on the forward stroke of the slide 14'.

The slide 14' has reciprocating motion imparted thereto from the drive shaft 28 by means of the crank connection 14', Figs. 1 and 4 of the drawings. By reference to Fig. 1 of the drawings, it will be noted that the motion of the drive shaft 28 is transmitted

to the shaft 3 for actuating the carrier disk 4 through the medium of the intermeshing gears 37 and 37', the gear 37' imparting motion to a cross shaft 38 carrying a worm 38' which meshes with a worm gear 39 on the shaft 3, the construction of the worm 38' being such as to impart intermittent rotation or movement to the worm gear 39.

Referring to Figs. 2, 4 and 5 of the drawings, it will be noted that the die ring 16 is provided with a series of rearwardly extending pins 16', which extend through bores 16² in the circular shoulder 16³ of the slide plunger 14', said pins bearing against an ejector ring 17² slidably mounted on the slide plunger 14' and which on the return stroke of the said plunger engages or contacts with the spring held slide pins 17³ working within guide bearings 17⁴ upwardly projecting from the bed 2.

The drive shaft 28 is driven in any suitable manner and on the forward stroke of the slide plunger 14' with the disk blank 21 positioned as in Fig. 4 of the drawings, the arms 35 are actuated to move outwardly the slides or slide plates 34-34' and the disk is forced against the fixed die 17, while the concentric punches 15 and 15' moving inwardly beyond the peripheral edge of the said die ring 17 cut or sever from the disk blank 21 the central core A, the annulus or ring liner B and the waste ring or trimming C, the cut annulus or ring liner being held between the opposing faces of the die rings 16 and 17; during which cutting action the follower ring 18' giving inwardly, the central core A is forced into the die ring 17 by the cutting punch 15 for gradual delivery into the magazine 18 by the accumulation of core pieces. On the return stroke of the said reciprocating slide plunger, the waste ring or trimming C of the cut disk blank is forced from off the stationary die ring 17 by the action of the spring follower 18', while the cut annulus or ring liner B adhering to the faces of the die punches 15-15' and the die ring 16, is carried outward beyond the seat 33 and in line with the discharge opening 33², when the ejector ring 17² acting against the spring held pins 17³ gradually moves the die ring 16 outwardly to force the cut annulus or ring liner B clear of the die punches 15 and 15', permitting the same to fall through the outlet opening 33² to within the sphere of the transversely horizontally disposed feed rollers 40-Figs. 2 and 4 of the drawings. The said feed rolls are mounted on the parallel shafts 40'-41, driven by the intermeshing gears 42, rotary motion being imparted to the shaft 41 from the driven shaft 38 by the drive belt 42 working over the belt pulleys 43-43' mounted on the shaft 41 and 38 respectively,-Fig. 1 of the drawings. The feed rollers 40 deliver the cut annulus or ring

liner B into one of the seats 5 of the carrier disk 4 through the segmental peripheral opening 11, communicating with the seat of the carrier disk 4 positioned to receive the same,-Fig. 2 of the drawings. During this removal operation of the cut annulus or ring liner B, it is required that the waste ring or trimmed material C of the disk blank 21 be disposed of, and for this purpose there is provided a reciprocating nipper or extracting device, comprising in the present case an arm 23^a depending from the rocker-shaft 23'-Fig. 7 of the drawings. This arm is inwardly curved at its lower extremity and said curved extension 24^a at its end has pivoted thereto a spring held nipper jaw 25^a-Figs. 4, 6, 7 and 8 of the drawings. The lower end of the swinging arm 23^a is supported by the curved bracket 26^a laterally projecting from the frame bed 2, and as the said arm is thrown inwardly the tail extension 25^b of the nipper jaw 25^a rides on the inclined face of a pivoted cam 27^a, for gradually throwing the tail extension 25^b inwardly to open the jaw 25^a so as to permit of the said jaw and the extreme end portion of the extension 24^a to embrace the peripheral edge of the waste ring C, Figs. 6 and 8 of the drawings. The lip on the follower 18' has a cut out portion, as shown in Figs. 6 and 7, to allow of the described action of the nipper. The tail extension 25^b moving off of or out of contact with the cam 27^a on the arm 23^a being swung inward its full distance, the pressure of the spring 28^a then exerts itself to force outwardly the tail extension 25^b to close the nipper 25^a to clamp the waste ring C, while at the same time the spring 29^a acting against the cam 27^a swings its free inner end outwardly to clear the depending section of the tail extension of the nipper jaw. With the waste ring or material C thus clamped, the same is removed and withdrawn from its seat during the outward throw of the arm 23^a, being so carried until the depending section of the tail extension 25^b of the nipper jaw engages with and rides again on the inner face of the cam bracket 26^a (Fig. 4), when the said jaw is opened and the waste ring C released for deposit at any suitable place-Fig. 7 of the drawings. During this removal of the waste ring or trimmed portion C of the disk 21, the pivoted holder or retaining guard 33' gives to the pressure exerted thereon, swinging upwardly to permit of the trimmed portion C being withdrawn. As the arm 23^a swings outwardly its full distance, the depending section of the tail extension 25^b of the nipper jaw moves off or out of contact with the inner face of the cam 27^a, permitting the said cam to return to normal position.

The core sections A which accumulate within the magazine are removed therefrom

and fed into a machine similar to the one herein described and from each of which is cut an annulus or ring liner for use in connection with can ends or covers of less diameter than the ones to which the present annulus or ring liner is to be applied.

The working stroke of the cutting mechanism, the action of the feed means for successively delivering disk blanks thereto, the removal of the waste material, the feeding of the cut annulus or ring liner to the mechanism for applying the same to the flange of can ends or covers are so regulated with respect to each other, that the various described actions successively come into play at predetermined moments, each part performing its desired work at the proper moment with respect to the other working parts of the apparatus, thereby constituting an automatic machine for the cutting of an annulus or ring liner from fed disk blanks by a single stroke of the die punch mechanism.

By the described apparatus, the necessity for employing an endless web for the cutting therefrom of the ring liners is obviated, equally so the complex mechanism for controlling and regulating the feed of such a web is dispensed with, and the cutting and feeding of the ring liners is performed with greater speed and accuracy than possible where a continuous traveling web is employed.

It will be understood that the expression "ring liner" is not limited to an annulus, but merely to designate a cut liner of proper shape to conform to the flange of the can end or cover to which it is to be applied, hence the term "disk blank" as herein employed is meant to express a blank of suitable shape from which the desired liner is to be cut.

The present invention is not limited to the details of working parts as herein shown and described, for these may be varied and modified without departing from the nature and spirit of the invention, and, therefore, I do not wish to be understood as confining myself to the disclosed arrangement of working parts, but, on the contrary, desire to cover as far as the art will permit, the combination of working features for carrying out the described operations.

Having thus described the invention what is claimed as new and desired to be protected by Letters Patent is:—

1. In an apparatus for the described purpose, the combination with a reciprocating die plunger, of concentric die punches carried thereby, a die ring movable on the plunger between the concentric punches, an opposing stationary die ring in alinement with the said movable die ring, a holder for a stack of disk blanks, means for successively removing the lowermost blank of the

stack of blanks within the holder and delivering the same individually between the opposing dies, means for guiding the individual blanks and arresting them in upright position between the dies, mechanism for actuating the punches to cut from the blank disk the central core and a ring liner, devices for actuating the movable die ring to eject the cut ring liner, and means for removing the waste of the blank from within the cutting mechanism.

2. In an apparatus for the described purpose, the combination with a holder containing a stack of disk blanks, of mechanism for cutting a central core, a ring liner and the waste portion from said blanks, devices for successively removing the lowermost blank from the stack of blanks within the holder and positioning the same within the cutting mechanism, rotary means co-acting with said cutting mechanism for receiving the can ends or covers and the cut ring liners and holding the same in spaced relation to each other, oppositely reciprocating devices carried by the rotary means and thrown into action by the movement thereof as each ring liner is cut and delivered thereto for applying the cut ring liner on to the flange of the can cover, and devices associated with the cutting mechanism for removing and discharging the individual waste material of each cut disk blank.

3. In a machine for the described purpose, the combination with reciprocating mechanism for cutting on a single stroke from a disk blank a central core and a ring liner of a diameter less than the diameter of a can cover, devices for delivering the disk blanks to the cutting mechanism, and a gripper for removing from the ring liner and from within the sphere of the cutting mechanism the waste material cut from the blank.

4. In a machine for the described purpose, the combination with a reciprocating die plunger, of a plurality of concentric cutting punches carried thereby, a die ring movable on the plunger between the concentric punches, an opposing stationary die ring in alinement with the movable die ring, means for successively delivering disk blanks in advance of the cutting punches, rotary means associated with the cutting punches for receiving the cut ring liner, and devices for removing the individual waste of each blank from the ring liner and from within the sphere of the cutting punches.

5. A machine for the described purpose, the same comprising reciprocating mechanism for cutting a ring liner and a central core and an exterior waste from a disk blank on a single stroke, means co-acting therewith for receiving can covers and the cut ring liners and applying the liners to the

flange of the can covers, means for successively delivering disk blanks to the cutting mechanism, and devices for automatically removing the exterior waste of each 5 cut disk blank from within the sphere of the said mechanism.

6. A machine for the described purpose, the same comprising horizontal reciprocating mechanism for cutting a ring liner and 10 a central core from a disk blank on a single stroke, means co-acting therewith for receiving can covers and the cut ring liners in upright positions and applying the liners to the flanges of the can covers, and means 15 for successively delivering individual disk blanks to the cutting mechanism.

7. In a machine for the described purpose, the combination with the reciprocating die punch mechanism for cutting from disk 20 blanks on a single stroke exterior waste portions and ring liners of less diameter than the diameter of a can cover, devices for receiving and positioning successively disk blanks relative to the cutting mechanism, 25 means associated with the said mechanism for receiving the cut ring liners and applying the same to the flange of can covers, and devices thrown into action by the actuating means of the cutting mechanism for removing 30 the exterior waste of the disk blank from within the said mechanism in advance of the operation of the said applying mechanism.

8. In an apparatus for the described purpose, the same comprising reciprocating 35 punch actuated mechanism for cutting on a single stroke from an individual disk blank a central core piece and an annulus or ring liner and an exterior waste, means associated therewith for receiving the cut ring liner and applying the same to the flange of a can 40 end or cover, and means for removing the individual exterior waste in advance of the operation of the said applying means.

9. In an apparatus for the described purpose, the combination with a plurality of 45 concentric die punches for cutting on a single stroke from a disk blank a central core piece and an annulus or ring liner and an exterior waste, of a die ring movable between the 50 concentric punches, means for imparting reciprocating motion to the said punches and die ring, an opposing fixed die ring, and devices for receiving and positioning a disk blank upright between the cutting punches 55 and the fixed die ring.

10. In an apparatus for the described purpose, the combination with a plurality of concentric die punches for cutting on a single stroke from a disk blank a central core piece 60 and an annulus or ring liner and an exterior waste, of a die ring movable between the concentric punches, means for imparting reciprocating motion to the said punches and die ring, an opposing fixed die ring, devices for receiving and positioning on edge a disk 65

blank between the cutting punches and the fixed die ring, means associated with the punch for receiving the cut ring liner and applying the same to the flange of a can end or cover, and devices for delivering the cut 70 ring liner to said means.

11. In an apparatus of the described character, the combination with cutting mechanism comprising a plurality of die punches and a die movably mounted between said 75 punches, an opposing die associated therewith, devices for positioning a disk blank on edge between said opposing instrumentalities, mechanism for actuating said instrumentalities to cut on a single stroke from 80 the disk blank a central core and a ring liner, and means arranged below the punches for receiving the cut ring liner and applying the same to the flange of a can end or cover.

12. In an apparatus for the described purpose, the combination with reciprocating mechanism for cutting on a single stroke from a disk blank a central core and a ring liner, devices for delivering and positioning 85 a disk blank relative to said cutting mechanism, means for receiving the central core of the blank, devices for delivering the cut ring liner to a suitable place of deposit, and means for removing from within the sphere 90 of the cutting mechanism the waste material 95 trimmed from the disk blank.

13. A machine for the described purpose, the same comprising in combination reciprocating mechanism for cutting on a single stroke from an individual disk blank a central core and a ring liner, means operatively connected therewith and arranged below the cutting mechanism for receiving a can end or cover and the said ring liner, and applying the latter to the flange of the can end 100 or cover, and operatively connected devices for delivering individual blank disks to the cutting mechanism and through the latter to the said liner receiving and applying 105 means.

14. A machine for the described purpose, the same comprising reciprocating mechanism for cutting on a single stroke from a disk blank a central core and a ring liner, means associated therewith and arranged below the same for receiving a can end or cover and the said ring liner, and applying the latter to the flange of the can end or cover, devices for delivering individual blank disks 110 successively and on edge to the cutting 115 mechanism, means for receiving the core removed from the disk blank, and devices thrown into action during the movement of the cutting mechanism for removing the waste material trimmed from said blank.

15. In an apparatus for the described purpose, the combination with cutting mechanism comprising co-acting instrumentalities for trimming a disk blank and cutting therefrom on a single stroke a central core and a 120 125 130

ring liner, of devices for positioning an individual disk blank and supporting the same on edge between the said instrumentalities, and means for removing the waste or trimmed material from within the sphere of the cutting mechanism.

16. In an apparatus for the described purpose, the same comprising co-acting instrumentalities for cutting on a single stroke from a disk blank a central core and a ring liner, mechanism for actuating said instrumentalities, means for grasping the waste while it is held on a cutting member for removing the waste, and means associated therewith and arranged below the same for receiving the cut ring liner and applying the same to the flange of a can end or cover.

17. In an apparatus for the described purpose, the combination with the cutting mechanism comprising opposing instrumentalities for trimming a disk blank and removing therefrom a central core piece and a ring liner, means for delivering disk blanks between said instrumentalities, devices for grasping the waste while it is held by the cutting mechanism for removing the waste or trimmed material of the disk blank from within the sphere of the cutting mechanism, and means associated with the cutting mechanism for receiving the cut ring liner and applying the same to the flange of a can end or cover.

18. In an apparatus for the described purpose, the combination with the cutting mechanism, of devices for delivering disk blanks thereto, and extracting means associated with the cutting mechanism for separating from the ring liner and removing the waste material from within the sphere of the cutting mechanism, the same comprising a reciprocating arm, a nipper jaw carried thereby, and devices for controlling the opening and closing movements of the said jaw.

19. An apparatus having embodied therein cutting mechanism for the described purpose, the same comprising co-acting instrumentalities for trimming an individual blank, cutting a ring liner and removing a central core piece and an exterior waste therefrom, in a single operation, delivering blanks to the cutting mechanism, extracting the individual exterior waste or trimmed material from within the sphere of the cutting mechanism, and associated mechanism for automatically actuating said instrumentalities for the work required.

20. In an apparatus for the described purpose, the same comprising co-acting cutting instrumentalities operating on a single stroke to trim a disk blank and cut therefrom a central core piece and a ring liner, an ejector device carried by one of said instrumentalities for the removal of the cut liner therefrom, devices for delivering disk blanks between the cutting instrumentalities,

and associated means for grasping the waste material while it is held by the cutting instrumentalities and removing it from within the sphere of the same.

21. A machine for the described purpose, 70 the same comprising horizontally reciprocating mechanism for trimming an individual disk blank and cutting therefrom in a single operation a central core and a ring liner, and horizontally operating means associated therewith and arranged below the same for receiving the ring liner and applying the same to the flange of a can end or cover.

22. In a machine for cutting and applying ring liners to can heads, in combination: 80 means for feeding individual blanks to be cut; punching mechanism arranged to receive such blanks successively, and having means for cutting a ring liner, a central core and an exterior waste; an applying mechanism for pressing the ring liners, successively as they are cut, into the can heads; means for feeding the ring liners from the said punching mechanism to the said applying mechanism; and means for separating and removing the individual exterior waste portions successively from the said punching mechanism.

23. In a machine for cutting and applying ring liners to can heads, in combination: 90 means for feeding edgewise and in upright position individual blanks to be cut; punching mechanism operating on substantially horizontal lines and arranged to receive 100 such blanks successively, and having means for cutting a ring liner, a central core and an exterior waste; an applying mechanism for pressing the ring liners, successively as they are cut, into the can heads; means for feeding the ring liners from the said punching mechanism to the said applying mechanism; and means for separating and removing the individual exterior waste portions successively from the said punching mechanism.

24. In a machine for cutting and applying ring liners to can heads, in combination: 110 means for feeding individual blanks to be cut; punching mechanism having an upright 115 receptacle arranged to receive such blanks edgewise and successively, and having means for cutting a ring liner, a central core and an exterior waste; an applying mechanism for pressing the ring liners, successively as they are cut, into the can heads; means for feeding the ring liners from the said punching mechanism to the said applying mechanism; and means for separating and removing the individual exterior waste portions successively from the said punching mechanism.

25. In a machine for cutting and applying ring liners to can heads, in combination: 120 means for feeding individual blanks to be 130

cut; punching mechanism arranged to receive such blanks successively, and having means for cutting a ring liner, a central core and an exterior waste; means for holding the blank upright between the punch members; an applying mechanism for pressing the ring liners successively as they are cut, into the can heads; means for feeding the ring liners from the said punching mechanism to the said applying mechanism; and means for separating and removing the individual exterior waste portions successively from the said punching mechanism.

26. In a machine for cutting and applying ring liners to can heads, in combination: means for feeding individual blanks to be cut; punching mechanism arranged to receive such blanks successively, and having means for cutting a ring liner, a central

core and an exterior waste; means for holding a blank upright between the punching members, such means being removable to allow of the operation of the punch members; an applying mechanism for pressing the ring liners, successively as they are cut, into the can heads; means for feeding the ring liners from the said punching mechanism to the said applying mechanism; and means for separating and removing the individual exterior waste portions successively from the said punching mechanism.

In testimony whereof I have signed my name to this specification in the presence of two subscribing witnesses.
